UNITED STATES PATENT OFFICE.

ANDREW J. WEEKLEY, OF EAST PITTSBURG, PENNSYLVANIA.

PNEUMATIC SIPHON.

SPECIFICATION forming part of Letters Patent No. 716,323, dated December 16, 1902.

Application filed April 4, 1902. Serial No. 101,379. (No model.)

To all whom it may concern:

Be it known that I, ANDREW J. WEEKLEY, a citizen of the United States of America, residing at East Pittsburg, in the county of Allegheny and State of Pennsylvania, have invented certain new and useful Improvements in Pneumatic Siphons, of which the following is a specification, reference being had therein to the accompanying drawings.

10 This invention relates to certain new and useful improvements in pneumatic siphons, and more particularly to that class of siphons whereby the sand, filings, and scales are removed from difficult recesses and spaces with-
15 in iron-molds and the like.

The object of my invention is to provide a siphon wherein the refuse to be removed from a mold may be rapidly performed without clogging or otherwise obstructing the passage.

20 Another object of the invention is to construct a device of this character that will be extremely simple, strong, durable, comparatively inexpensive to manufacture, and highly efficient in its use.

25 With the above and other objects in view the invention consists in the novel construction, combination, and arrangement of parts to be hereinafter more fully described, and specifically pointed out in the claims.

30 In describing the invention in detail reference is had to the accompanying drawings, forming a part of this specification, and wherein like numerals of reference indicate like parts throughout both views, in which—

35 Figure 1 is a side elevation of my improved siphon. Fig. 2 is a longitudinal section of the body portion of my improved siphon.

In the drawings the reference-numeral 1 represents the body portion of the siphon, which 40 conforms in shape similar to that of a T or elbow of ordinary piping. This body portion 1 has formed in its outer end 2 an aperture 3, said aperture carrying screw-threads 4. The inlet or aperture 3 has its inner bore 45 downwardly deflected, as seen at 5. In the opposite end 5 of the siphon is an aperture or opening 6, said opening being screw-threaded, as indicated at 7, the diameter of said opening being greater than the opening 3. In the 50 lower face of the siphon 1 is a screw-threaded aperture 8, said aperture having its diameter

smaller than the aperture 6 and larger than the opening 3, the lower face of the siphon having a projecting side 9, which is formed, preferably, as shown in Fig. 2 of the drawings. 55 Connected to the opening 3 is the compressed-air supply 10, said supply being fed by means of a valve 11, this supply being furnished by any suitable means. (Not shown in the drawings.) In the screw-threaded aperture 60 8 is secured a pipe 12, said pipe being formed of any suitable material, preferably rubber. Secured in the aperture 6 is a pipe 14, said pipe carrying the refuse to any desired receptacle or outlet. 65

The operation of my improved siphon is as follows: In the art of molding considerable trouble has been experienced in removing the sand, filings, and scales from difficult and small recesses, and to overcome this I have 70 provided a siphon wherein the suction-pipe 12 may be inserted in such recesses and the refuse readily removed from the same. The sand or refuse is generally broken or disintegrated by means of a rod or other suitable 75 means, whereby the sand is in that condition that it may be readily drawn through the suction-pipe. Having inserted the suction-pipe within the recess, the valve 11 is turned, allowing any desired amount of compressed air 80 to travel through the siphon 1, said passage of air being sufficient to cause the suction through the pipe 12, whence the sand is withdrawn and passes through the outlet 14 to any desired receptacle. By constructing my 85 siphon to conform to the shape shown in Fig. 2 I overcome the clogging or congestion of the siphon, great trouble having been experienced in this line by a congestion of the sand in the body portion of the siphon. By 90 making the enlarged portion 9 on the lower side of my improved siphon I afford means whereby the sand will readily find the outlet 6, where the compressed air will aid the same to its destination. This enlarging of the body 95 in this manner enlarges the chamber, and this enlargement is at a point immediately above and to the left of the discharge from the pipe 12 into the chamber, and hence any lumps or other bodies of solid material drawn 100 up the pipe 12 are readily conducted to the outlet 6, since they are not required to make

a turn in the chamber at direct right angles to the pipe 12. The opening 6 is made of considerably greater diameter than the inlet 3, whereby a free escape for the air is provided and a greater suction obtained through the pipe 12.

The many advantages obtained by the use of my improved siphon will be readily apparent from the foregoing description, taken 10 in connection with the accompanying drawings.

It will be noted that various changes may be made in the details of construction without departing from the general spirit of my 15 invention.

Having fully described my invention, what I claim as new, and desire to secure by Letters Patent, is—

1. In a pneumatic siphon, the combination 20 of a body portion, an air-inlet, a refuse-inlet and a common outlet formed therein, said body portion being provided with an inclined side between said refuse-inlet and said outlet-port, and means provided in said air-inlet for

deflecting the injected air against said inclined side, substantially as described. 25

2. In a pneumatic siphon, the combination of a body portion having formed therein, inlets and an outlet, said inlets being of smaller bore than the outlet, one of said inlets having the inner end of its bore downwardly deflected, and an inclined side approximately opposite said deflected inlet, substantially as described. 30

3. In a pneumatic siphon, the combination 35 of a body portion, an air-inlet, a refuse-inlet arranged below and being of larger diameter than said air-inlet, and an outlet of larger diameter than said inlets, and means for deflecting the injected air against the wall of 40 the body portion between said refuse-inlet, and said outlet, substantially as described.

In testimony whereof I affix my signature in the presence of two witnesses.

ANDREW J. WEEKLEY.
